(57) **CLAIM**

I claim the ornamental design for a multi-function stylus, as shown and described.

DESCRIPTION

FIG. 1 is a Perspective view of a multi-function stylus showing my new design;

FIG. 2 is a Front view of the multi-function stylus as shown in FIG. 1;

FIG. 3 is a Back view of the multi-function stylus as shown in FIG. 1;

FIG. 4 is a Left-side view of the multi-function stylus as shown in FIG. 1;

FIG. 5 is a Right-side view of the multi-function stylus as shown in FIG. 1;

FIG. 6 is a Top view of the multi-function stylus as shown in FIG. 1;

FIG. 7 is a Bottom view of the multi-function stylus as shown in FIG. 1;

FIG. 8 is Two-side open view of the multi-function stylus as shown in FIG. 1;

FIG. 9 is One-side open view of the multi-function stylus as shown in FIG. 1; and,

FIG. 10 is other side open view of the multi-function stylus as shown in FIG. 1.

The broken lines are only for environmental purposes and form no part of the claimed design.

1 Claim, 9 Drawing Sheets
